DESIGN FOR A SHADE-BOWL.

49,639.

Specification for Design.

Patented Sept. 12, 1916.

Application filed June 30, 1916. Serial No. 106,983. Term of patent 7 years.

To all whom it may concern:

Be it known that I, JOHN BEISWANGER, a citizen of the United States of America, and resident of Steubenville, county of Jefferson, State of Ohio, have invented a certain new, original, and ornamental Design for a Shade-Bowl, of which the following is a specification.

In the accompanying drawing, which is a perspective view taken from the side, I have illustrated a reflector shade constructed in accordance with my invention.

The device consists of a bowl 1, substantially in the form of an acorn, having a series of juxtaposed vertical flutes 2 occupying the central zone, the termination 3 of the flutes being sharply defined at the top,

the flutes disappearing or gradually shading down to a smooth curved surface including the entire lower portion of the bowl which has a button or knob 4 at the bottom representing the point of the acorn, a smooth top portion 5 and a crown 6 representing a conventionalized shell.

Having thus described and illustrated my invention, I claim:

The ornamental design for a shade bowl, substantially as shown and described.

Signed by me at Steubenville, Jefferson county, Ohio, this 8th day of June, 1916.

JOHN BEISWANGER.
